UNITED STATES PATENT OFFICE.

JOHN W. FOSTER, OF CHICAGO, ILLINOIS, ASSIGNOR TO ARTHUR HARRISON & COMPANY, OF CHICAGO, ILLINOIS, A CORPORATION OF ILLINOIS.

DESIGN FOR A LIGHTING FIXTURE.

Application filed December 17, 1928. Serial No. 29,304. Term of patent 14 years.

To all whom it may concern:

Be it known that I, JOHN W. FOSTER, a citizen of the United States, and resident of Chicago, in the county of Cook and State of Illinois, have invented a new, original, and ornamental Design for a Lighting Fixture, of which the following is a specification, reference being had to the accompanying drawing, forming a part thereof.

Figure 1, is an elevational view of a lighting fixture, showing my new design; and

Figure 2 is a fragmentary bottom plan view of the same, the balance of the ornamentation within the outline being a repetition of the fragment shown.

My new design comprises a canopy 1, which is constructed of metal or analogous material, and a rosette 2, associated therewith, which rosette is of glass or analogous material. The said rosette may be of any desired color, and the design or shape of which, and the ornamentation thereon, is substantially as shown in the drawings.

I claim:

The ornamental design for a lighting fixture substantially as shown, and described.

Signed at Chicago, in the county of Cook, and State of Illinois, this 23rd day of November, A. D., 1928.

JOHN W. FOSTER.
